UNITED STATES PATENT OFFICE.

ADOLPH SIMON, OF LONDON, ENGLAND.

SLACK-ABSORBER FOR BRACELETS OR THE LIKE.

1,313,645.

Specification of Letters Patent.

Patented Aug. 19, 1919.

Application filed February 28, 1919. Serial No. 279,916.

To all whom it may concern:

Be it known that I, ADOLPH SIMON, a subject of the King of England, residing at London, England, have invented certain new and useful Improvements in Slack-Absorbers for Bracelets or the like, of which the following is a specification.

This invention relates to expandible bracelets or the like, and a primary object is to provide a more simple form of absorber for the slack of a bracelet or the like than that described in my co-pending patent application, Serial No. 224,993, filed March 27, 1918.

The slack-absorber described in the above-mentioned co-pending patent application is built up of several parts in addition to the roller, and another object of the invention is to simplify the assembling of the parts of a slack-absorber of the kind referred to.

20 A further object is to provide for the roller a single-piece sheet-metal frame wherein the roller can be locked in position, and providing guides for the ribbon to be taken up by the roller.

25 A still further object is to provide that the slack-absorber comprising the single-piece frame shall nevertheless have the appearance of a buckle as in the case of known slack-absorbers of the kind referred to.

30 A still further object is to provide that the roller-spindle can be dropped into place in the single-piece frame after its one end has been entered into a hole of the one side of the frame, and can then be locked in position by bending a horn or lug provided on the opposite side of the frame.

To this and other ends, the invention consists in the construction, arrangement and combination of parts described hereinafter and pointed out in the claims.

40 One embodiment of the invention is illustrated by way of example in the accompanying drawing, wherein:

Figure 1 is a top plan view of a flat blank from which the frame of a slack-absorber is to be made,

Fig. 2 is a perspective view showing the blank bent up to form the frame for carrying the roller,

50 Fig. 3 is a vertical longitudinal section through the frame and roller showing means fixing the roller-spindle in position, and

Fig. 4 is an end elevation of the slack-absorber showing Fig. 3 as viewed from the left of that figure.

Like reference letters designate like parts in all the views.

Referring first to Fig. 1, a four-sided blank A has a central, square aperture or orifice A¹. Opposite sides B, B¹ of this blank bound the orifice A¹ in two directions, and intermediate side pieces C, C¹ are provided on the blank, these pieces being perforated at C² so that they constitute little more than wire loops. The side piece B has a slot B² in it, and in line with this is an outwardly-projecting lug or horn B³; the side piece B¹ has a circular hole B⁴ in line with the slot B² and the lug B³. The blank thus formed has the side pieces B, B¹ bent up at right-angles to the part A, as shown in Fig. 2, to provide supports for the roller, and the intermediate side pieces C, C¹ similarly bent at right-angles to the part A to form guides for the ribbon which is applied to the roller in the same manner as is described in the above-mentioned co-pending patent application.

The horn B³ is bent outward from the ear B and the bend is made sufficiently far down the ear to expose the top of the slot B², as shown at B² in Fig. 2. It thus follows that a roller D having a spindle D¹, Fig. 3 can be brought into position after the frame is made up by first inserting one end of the spindle D¹ into the hole B⁴ in the ear B¹, and then swinging the roller down as indicated by the arrow, so that the other end, which is squared, enters the slot B² and can be brought to the bottom of the said slot. The horn B³ is then bent over so that its end lies against the spindle, as shown in Fig. 3, and prevents it from rising out of the slot. A spring for operating the roller is shown at E, Fig. 3, and has one end secured to the spindle and the other end to the roller, as is described in the above-mentioned co-pending patent application.

The operation of the absorber is the same as that described in the above-mentioned co-pending patent application, a ribbon F being engaged with the roller and threaded through the guides C, C¹ in the same manner as is therein described, but the advantage of the present construction is that the whole article contains only four pieces, viz: (1) the frame, (2) the roller, (3) the spindle and (4) the spring. The roller in the drawings is shown only diagrammatically as its construction forms no part of the present invention.

vention, but if it is provided with a detachable cap as shown and described in the above-mentioned co-pending patent application, this cap would constitute a fifth piece.

5. Should the roller require to be repaired, or a new spring inserted, the horn B^3 is easily bent outward so that that end of the roller-spindle can be lifted from the slot and then the whole roller drawn out from the frame.

10. These articles are usually made in gold, which is very malleable, and therefore lends itself well to this manner of construction, but rolled gold, silver or other metals can be 15 employed in the same manner.

If desired, a lug performing the same function as the horn B^3 could be stamped up when making the slot B^2 , its end being then attached to that end of the slot which is nearest the orifice A^1 . With the lug in this position, it would be bent over the end of the 20 spindle when in place in the slot, and the slot could be continued out to the edge of the ear, so that no bending would be necessary at the point where the lug is attached 25 in the construction shown in the drawings.

It will be seen that all the parts of the slack-absorber frame constructed according to this invention are necessary to the construction and operation, so that there is no waste material. Thus, the ears B , B^1 carry 30 the roller, the lug B^3 secures it, the loops C , C^1 are guides for the ribbon, and the parts of the plate A which are not bent up, serve 35 both as guide-portions and as strengthening-pieces to connect the ears B , B^1 .

What I claim as my invention and desire to secure by Letters Patent is:—

1. A slack-absorber of the character de-

scribed, the combination with a roller, of 40 a single-piece sheet-metal frame having two opposite sides bent down to constitute two supporting-ears carrying each one end of the roller, and the two intermediate opposite sides perforated and bent down to constitute guides for a ribbon to be taken up on the roller.

2. In a slack-absorber of the character described, the combination with a spindle, and a roller thereon, of a single-piece sheet-metal frame having two opposite sides bent down to constitute two supporting-ears, whereof the one has a round perforation through which extends the one end of said spindle, and the other supporting-ear has a slot 50 through which extends the other end of said spindle, the latter supporting-ear having a bent lug or horn normally locking the latter end of the spindle in said slot, the two intermediate opposite sides of the frame being 55 perforated and bent down to constitute guides for a ribbon to be taken up on the roller.

3. As a new article of manufacture, a four-sided, single-piece, sheet metal blank, 60 for a slack-absorber frame, having a central rectangular aperture, whereof one of two opposite sides has a circular hole situated midway between its ends and the other of said opposite sides has a slot which is situated midway between its ends and is directed toward said hole, and has a horn or lug extending in line with said slot and said hole, and the two remaining opposite sides are perforated to constitute guides, substantially as shown.

In testimony whereof I affix my signature.

ADOLPH SIMON.
